CLAIM

The ornamental design for an inhalation device, as shown and described.

DESCRIPTION

FIG. 1 is a top perspective view of an inhalation device in a first configuration according to our new design;

FIG. 2 is a front view of the inhalation device of FIG. 1;

FIG. 3 is a rear view of the inhalation device of FIG. 1;

FIG. 4 is a right side view of the inhalation device of FIG. 1;

FIG. 5 is a left side view of the inhalation device of FIG. 1;

FIG. 6 is a top view of the inhalation device of FIG. 1;

FIG. 7 is a bottom view of the inhalation device of FIG. 1;

FIG. 8 is a top perspective view of the inhalation device in a second configuration;

FIG. 9 is a front view of the inhalation device of FIG. 8;

FIG. 10 is a rear view of the inhalation device of FIG. 8;

FIG. 11 is a right side view of the inhalation device of FIG. 8;

FIG. 12 is a left side view of the inhalation device of FIG. 8;

FIG. 13 is a top view of the inhalation device of FIG. 8; and,

FIG. 14 is a bottom view of the inhalation device of FIG. 8.
